UNITED STATES PATENT OFFICE.

ALOIS LISSNER, OF TETSCHEN, AUSTRIA-HUNGARY.

KEYHOLE-GUARD.

1,079,654.

Specification of Letters Patent. Patented Nov. 25, 1913.

Application filed July 9, 1912. Serial No. 708,475.

To all whom it may concern:

Be it known that I, ALOIS LISSNER, locksmith, subject of the Emperor of Austria-Hungary, residing at Tetschen a. Elbe, Austria-Hungary, have invented certain new and useful Improvements in Keyhole-Guards, of which the following is a specification, reference being had therein to the accompanying drawing.

- 10 This invention relates to an improved key-hole guard, which is compulsorily engageable and disengageable together with the outer keyhole-cover. The device is arranged behind the keyhole and permits, when in
15 engaged position, of a lateral displacement of the keyhole-cover to a certain extent only, without the device being influenced itself. The disengagement of the locking device is effected by means of a socket-key, which is
20 introduced into a slot rendered accessible by such a partial lateral movement of the key-hole-cover. Thereby, tumblers connected with the ratchet-bolt, are moved out of an
25 arresting bar and remain disengaged by action of a spring acting upon the ratchet-bolt during the introduction of the key, so that by a further turning of the outer keyhole-cover, which is then possible, and a consequent movement of the inner ratchet-bolt
30 the keyhole is liberated.

In the accompanying drawing, the improved device is shown.

Figure 1 is a rear view of the same, with back-wall removed. Fig. 2 is a sectional side
35 view of the same, on the line A—B of Fig. 1. Fig. 3 is a cross-section on the line C—D of Fig. 1. Fig. 4 shows a modification of the ratchet-bolt.

The device is separate from the lock
40 proper and is let into the front side of the door so as to be flush therewith, it being fixed thereto by screws *v* inserted from the rear and engaging an upper and lower rigid part *u* of the device.

45 The device comprises a casing *a*, provided in the front side with a slot *b*, for the introduction of a socket-key, and further with an ordinary keyhole *c*. Over the slot *b* and the keyhole *c* a keyhole-cover *d* is pivoted.
50 The pivot of the latter carries within the casing a lock-nut *e* with a ward *f*. The ward and nut rest in the recess of a keyhole closing ratchet-bolt *h* movably arranged in guides *g*. The ward *f* bears against a
55 shoulder *i* of the recess, when the keyhole-cover *d* is in closing position (see full lines,

Fig. 1). In the horizontal plane of the slot *b* for the insertion of the socket-key, tumblers *l*, which are movably attached to the ratchet-bolt *h*, are arranged so as to engage an arresting bar *k*, which is rigidly fixed in the casing. Said tumblers are acted upon by springs *q* in such a way that their ends *m* are held in line with a shoulder *n* of the arresting bar, when the device is in its
60 engaged position (Fig. 3). The tumblers being mounted at *o* on the ratchet-bolt *h*, they prevent the latter from being moved to uncover the keyhole, as long as they are in engagement with the arresting-bar.

70 The operation of the device is as follows:—For its disengagement, the keyhole-cover *d* is laterally moved into the position shown by dotted lines in Fig. 1. The slot *b* is then accessible, and the ward *f* bears
75 against the side *r* opposite to the catch *i* of the recess in the ratchet-bolt *h*. The socket-key *s* being then introduced (Fig. 3), causes the tumblers *l* pivoted to the ratchet-bolt *h* to be moved out of alignment with shoulder *n* on bar *k*, the spring *t* moving the ratchet-bolt *h* far enough to allow the ends of tumblers *l* to pass shoulder *n* and to rest upon the surface of the arresting bar *k*. The ratchet-bolt *h* is thus released and the keyhole-cover *d* can now be turned farther, moving bolt *h* away from the keyhole, by means of the ward *f* pressing against the recess-side *r*. To again lock the keyhole, the cover *d* is moved back over the same, whereby the
80 ward *f* presses against the shoulder *i* of the ratchet-bolt *h* and thus moves the latter into its initial position. The tumblers *l* slide then, by action of their springs *q*, from the surface of the arresting bar *k* behind the
85 shoulder *n* of the latter, whereby the keyhole is again closed.

90 In the modification of the ratchet-bolt *h* shown in Fig. 4, the forward and backward movement thereof is carried out by the bolt
95 turning on a fixed point *w*.

I claim:

100 A keyhole guard, comprising in combination, a casing having in its front side a key-hole and an insertion-slot for a socket-key, a keyhole cover, a pivot pin to mount the latter on the outer side of the casing, a ratchet-bolt arranged within the casing and having a recess, a fixed ward on the pivot pin of the keyhole-cover arranged within
105 said recess and adapted to permit of the keyhole-cover being freely turned so far only
110

that the insertion-slot becomes accessible, an arresting bar fixed in the casing behind the insertion-slot, spring-pressed tumblers movably mounted on the ratchet-bolt and adapted to normally engage said arresting bar but to be disengaged therefrom upon introduction of a socket-key in the insertion-slot, and a spring to laterally shift said ratchet-bolt and thus also the tumblers upon the lat-

ter being disengaged, substantially as and for the purpose set forth.

In testimony whereof I affix my signature in the presence of two witnesses.

ALOIS LISSNER.

Witnesses:

KARL KAUL,
JOSEF WEBER.
